SELECTIVE CONTROL APPARATUS

John J. Alles, Wilkes-Barre, Pa.

Application March 25, 1950, Serial No. 151,885

13 Claims. (Cl. 177—337)

1

This invention relates to selective control apparatus and, while not limited thereto, is herein illustrated and described in connection with a street traffic signaling system, wherein green, amber and red signals are operated through repeated cycles.

In order to maintain a smooth flow of traffic on long streets or boulevards, it is not uncommon for the traffic lights at successive intersections to be so timed that, traveling at some given speed, the traffic can move from one end of the street to the other without encountering a red light. As is well understood, a timing pattern for such an arrangement is equally effective for traffic moving in both directions on the street in question, only if all of the distances between successive traffic lights are equal. Such ideal spacing is the exception rather than the rule; and, accordingly, the common need is for a timing pattern to permit uninterrupted flow in the direction appropriate for the morning "rush hours" and in the opposite direction in the evening "rush hours" when the major flow is reversed.

In order to meet this need, the practice has developed of installing what amounts to duplicate controllers, differently timed and of using one controller in the morning hours and the other in the evening hours. In many instances, still another controller is utilized for actuating the traffic lights throughout some intervening period when the traffic pattern is still different.

In its herein illustrated application to traffic controllers, the primary object of the present invention is a control apparatus which, without the aforesaid duplication, can serve to activate any one of several timing patterns, each of which may itself be adjusted independently of the others.

For purposes of illustration, the invention is shown applied to traffic signal control apparatus of the kind illustrated in my prior patent, No. 2,324,051, dated July 13, 1943.

The invention consists in the novel features and in the combinations and constructions hereinafter set forth and claimed; and as exemplified in the accompanying drawings, in which:

Fig. 1 is a schematic diagram showing both the wiring and mechanical components of a three unit controller embodying the invention;

Fig. 2 is a partially-sectioned, side elevational view of a controller, corresponding to Fig. 5 of my said prior patent but incorporating the present invention;

Fig. 3 is a front elevation of the timer disc of the controller of Fig. 2; and

2

Fig. 4 is a schematic showing of a modification.

The controller of the said prior patent is made up of a number of identical units, each unit serving to illuminate successively a set of green, amber and red signals. In other words, one unit serves to control the flow of traffic on one street, so that at the common crossing or two-street intersection, the controller incorporates two units; and at a three-street intersection, the controller incorporates three units. Each unit incorporates what for convenience will be termed a signal control shaft, adapted to be rotated forwardly from a stop position to a limit position, to effect successive energization of the signal light circuits. The shaft then returns or rotates backwardly to its initial stop position preparatory to repeating the cycle. Regardless of the number of units, each one is started on its forward movement in response to the completion of the cycle of one of the other units in the controller.

In the arrangement, diagrammatically illustrated in Fig. 1 of the drawings, provision is made for controlling the lights at a three-street intersection, the three units being designated A, B and C. The green, amber and red lights controlled by unit A are designated 10, 11 and 12; those controlled by unit B as 13, 14 and 15; and those controlled by unit C as 16, 17 and 18. For convenience, the green, amber and red signal lights are lettered G, A and R, respectively, in all three of its units.

As described in the aforesaid prior patent, the signal lights 10, 11 and 12 are connected to the common side 20 of the supply through a wire 21 and signals 13, 14 and 15 are connected to the side 20 through wire 22; the signals 16, 17 and 18 through wire 23. The green signal 10 is connected to contact 24 through wire 25, and the amber light 11 to a contact 26 through wire 27. In like manner, the green and amber signals 13, 14 are connected to contacts 28, 29 respectively through wires 30, 31, and the green and amber lights 16, 17 to contacts 32, 33, through wires 34, 35.

A movable contact 36 is arranged to be moved into and out of engagement with the contacts 24, 26, and is connected to a stationary contact 40 through wire 41. The contacts 28, 29 are controlled by movable contact 42 connected to stationary contact 43 through wire 44; and the contacts 32, 33 are energized by moving contact 45 connected to contact 46 through wire 47.

Contact 40 is energized by the armature or movable contact 50 connected to the hot side 51 of the supply through wire 52. The armature 50 is under the control of a relay coil 53. The

contact 43 of unit B is energized by armature 54 connected to wire 51 through wire 55, the armature being under the control of relay coil 56, and the contact 46 of unit C is energized by armature 58 connected to wire 51 through wire 59, this armature being controlled by relay 60.

The contacts 36, 42, 45 are actuated into and out of engagement with their associated stationary contacts by cams 62, 63, 64. These cams are mounted upon and rotate with control shafts 66, 67 and 68, respectively, these shafts being rotated by motors 69, 70, 71 through reduction gearing arranged in the respective gear housings 72, 73, 74. The motors 69, 70, 71 are connected to the gearing in housings 72, 73 and 74 through their shafts 75, 76 and 77, respectively. The cams 62, 63 and 64 may be insulated from their shafts 66, 67, 68, by being mounted upon discs 78 of insulating material.

A helical spring 90 is secured at its inner end to shaft 66, as at 91, and at its outer end to a fixed point 92. The arrangement is such that when the shaft 66 is rotated to move the cam 62 through its arc of rotation, the spring 90 is wound up. That is, the rotation of the shaft 66 is against the tension of the spring and, accordingly, the spring 90 yieldingly urges the shaft 66 and the associated cam 62 back to its initial position. Similarly, a spring 93 is associated with shaft 67 and a spring 96 with shaft 68.

The cam 62 in unit A is in its initial or starting position with movable contact 36 in engagement with contact 24. However, the green signal 10 is not illuminated due to the fact that relay 53 is de-energized and its armature 50 is out of engagement with contact 40 and is dropped into engagement with stationary contact 100 which is connected to the red lamp 12 through wire 101. Accordingly, the red light is energized on street A.

Cam 63 of unit B has traveled through its arc of movement and has come to rest with the highest part of the lobe 103 of the cam in engagement with the movable contact 42 and has thus moved contact 42 into engagement with contact 29. However, the amber light 14 is not illuminated due to the fact that relay 56 is also de-energized, thus breaking the feed circuit to contact 43. The red light 15 is, however, energized through wire 55, armature 54, contact 105 and wire 106.

Cam 64 in unit C has traveled through a portion of its arc of movement and is so positioned that the low part of the cam lobe 107 is in engagement with the contact 45 and has moved the same into engagement with contact 33. Inasmuch as the relay in unit C is now energized, a hot feed is provided to the amber light through wire 59, armature 58, contact 46, wire 47, contacts 45, 33, and wire 35. Relay 60 in unit C is energized through wire 55, armature 54, wire 106, wire 108, movable contact 109, stationary contact 110, wire 111, wire 112, to the common side 20. Wire 111 is also connected to coil 113 of motor 71 through wire 114, the opposite side of the coil being connected to wire 112 to the common return 20. Accordingly, the motor 71 is energized and is operating to effect rotation of cam 64.

From the above description, it is apparent that motors 69, 70 of units A and B are de-energized and their red lights 12, 15 are displayed. Motor 71 of unit C is energized, cam lobe 107 having just shifted the movable contact 45 from contact

32 to contact 33, effecting a shift from the green signal 16 to the amber signal 17 of unit C.

The gear housings 72, 73, 74 are each provided with radially extending projections 120, and the respective units are provided with detents 121, 122 and 123 normally engaging the projections 120 and being withdrawn from engagement therewith by the respective solenoid coils 125, 126 and 127. One side of the coil 127 is connected to the wire 112. Similarly, the coil 125 is connected to the wire 128 and the coil 126 to the wire 129. The opposite side of coil 125 is connected through wire 130 to the feed wire 35 for the amber lamp 17 on street C. The other side of the coil 126 is connected through wire 131 to the feed wire 27 of the amber lamp 11 for street A, and the opposite side of coil 127 is connected through wire 134 to the feed wire 31 for amber lamp 14 on street B.

Accordingly, inasmuch as amber lamp 17 on street C is illustrated as energized, the coil 125 is likewise energized, moving the detent 121 out of engagement with the projections 120 on gear housing 72. The reduction gearing in the housings 72, 73, 74 is of the planetary type and functions when the housings are held against rotation to effect rotation of the cam shafts by the respective motors. Due to the relatively great reduction in the gearing arranged in each of the housings 72, 73, 74, the housings are in practical effect, insofar as retrograde movement is concerned, coupled to the respective shafts 66, 67, 68. Accordingly, when the shafts 66, 67, 68 have been rotated through their cycle or arc of movement by their respective motors against the tension of the springs 90, 93, 96, and thereupon the detents 121, 122 and 123 are withdrawn from the projections 120, the housings 72, 73, 74 and their associated shafts 66, 67, 68 are rotated backwards by the springs 90, 93, 96.

According to the present invention, means are provided for remotely varying the limit of backward movement of the shafts 66, 67, 68 or, in other words, for establishing different starting positions for each shaft and cam. By such means, as will be understood, the durations of the green signals are increased or decreased. In general, such means comprises a plurality of stop means, providing as many different starting positions as there are timing patterns to be provided for. That is to say, two starting positions for two patterns (such as morning and evening) or three starting positions if an intermediate pattern is also required. These stop means are described in detail below.

Reverting now to the description of the general operation of the system, it will be noted that with the illumination of the amber lamp 17 on street C, cam unit A is returned to its initial position, as indicated in the diagram.

The moving contacts 36, 42, 45 are so arranged, or the co-acting stationary contacts 26, 29, 33 are so arranged as to permit a slight over-movement. That is, when the low portion of the lobe 107 on cam 64 engages the contact 45, it moves the same into engagement with contact 33, and then effects further movement of contact 45, causing the insulating member 129 to engage adjusting screw 140, moving contact 109 out of engagement with contact 110, thereby breaking the feed circuit to relay 60 and motor coil 113. Accordingly, cam unit C stops in this position, retrograde movement by spring 96 being prevented because of the fact that detent 123 is in engagement with the projections 120 on gear

housing 74. De-energization of relay 60 effects display of the red signal 18 on street C through movable contact 53, stationary contact 142, wire 143.

Units A and B are provided with movable contacts 144, 145 respectively, which contacts are comparable to contact 109 of unit C. Each of the movable contacts 144, 145 is also provided with adjusting screws 140. It will be apparent that when contacts 109, 144, 145 are moved out of engagement with their respective stationary contacts, the associated amber light is extinguished. Accordingly, the time within which the movable contacts are actuated determines the duration of the amber. Hence, the duration of the amber is adjustable by adjusting the screws 140.

As previously explained, when the amber lamp 17 on street C is energized, solenoid coil 125 of unit A is also energized, retracting the detent 121 from engagement with the housing 72, thus permitting cam 62 to return to its initial position, as shown. Subsequently, when the red light 18 of unit C is energized, relay 53 of unit A is energized through wire 150 which connects wire 143 to contact 144 which, at this time, is in engagement with contact 151, the latter being connected by wire 152 to the motor coil 153 of motor 69 and by branch wire 154 to the solenoid 53, the wire 129 serving as a return circuit for relay 53, coil 125 and motor coil 153.

At this juncture, with the green signal displayed by unit A and red signals by units B and C, unit A commences its signal change cycle. At the end of the period of display of the green signal and when the circuit of the amber signal is completed, coil 126 of unit B is energized and detent 122 drawn out of engagement with housing 73, permitting shaft 76 to return to its initial stop position. Now when the unit A advances to its final position and moves contact 144 out of engagement with contact 151, relay 53 will be de-energized, permitting contact 50 to move out of engagement with contact 40, thus extinguishing the amber lamp 11 and moving into engagement with contact 109 to energize the red signal 12 through wire 161 and thereupon through wire 157, contacts 145, 153, wire 159. The motor coil 160 of motor 70 will be energized to actuate cam 63 on its cycle and simultaneously the relay 56 will be energized through branch wire 161, in this instance the wire 128 serving as a common return for both relay 56 and motor coil 160.

This operation effects movement of contact 54 out of engagement with contact 105 and into engagement with contact 43. This completes a circuit from the hot side of the line 51 to the green light 13 on street B through wire 44, movable contact 42, contact 28, wire 30, green light 13 and thence to the common side 20 through wire 22.

Unit B continues to operate through its cycle, shifting contact 42 out of engagement with contact 28 and into engagement with contact 29, thus extinguishing the green light 13 and energizing the amber light 14 and simultaneously energizing coil 127 of unit C, causing the detent 123 to move out of engagement with the housing 74 and permitting cam 64 to return to its initial stop position; and at the end of its travel, as illustrated in Figure 1, cam 63 has moved contact 145 out of engagement with contact 158 breaking the circuit to relay 56 and effecting display of the red signal 15 as previously described.

The individual control units are thus operable through a cycle to successively display the green,

amber and red signals on their respective streets, and are also operable to shift or return one of the other units to its initial stop position, and upon display of the red light to initiate another one of said units on its cycle.

In the arrangement disclosed in my said prior patent, means are provided for effecting adjustment of the initial stop position of each of shafts 66, 67, 68, so that by manual manipulation of the controls of each controller, any required time pattern for the signals can be obtained.

According to the present invention, a plurality (more than one, as used herein) or set of stops is provided for each of shafts 66, 67, 68 or for as many control shafts as there may be units in the controller, the number of stops determining the number of different timing patterns from which any one pattern can be remotely selected, simultaneously, for as many units and controllers as desired.

As illustrated in the diagram, Fig. 1, three discs 165, 166, 167 are shown as adjustably secured to shaft 66, the discs having projecting ears or stop elements 168, 169, 170. Cooperating stop elements 171, 172, 173 are also indicated. These latter are conveniently referred to as the "stationary" stop elements, in that they do not rotate with shaft 66. As illustrated, however, they are pivotally mounted, being normally biased to 30 positions to avoid engagement by their corresponding stop elements 168, 169, 170, and being selectively movable into position to be so engaged by coils 174, 175, 176, respectively.

It will thus be apparent that by adjusting the 35 three discs 165, 166, 167 about shaft 66, their stop elements 168, 169, 170 can be so located as to provide, in cooperation with their respective stop elements 171, 172, 173, three different stop or initial positions to which the shaft 66 will 40 be returned under the influence of its spring 90. By thus predetermining three different starting points and hence three durations for the green signal, any one of three timing patterns can be activated by merely energizing one of the coils 174, 175, 176. The stop elements 171, 172, 173 are designed to yield if and when engaged by elements 168, 169, 170 during forward movement of shaft 66, so that they serve only to arrest or limit the backward movement of the shaft. 45 To that end, stops 171, 172, 173 may be formed of flexible material.

In the diagram, Fig. 1, three similar coils 177, 178, 179 and 180, 181, 182 are shown in identical arrangement for units B and C, respectively, 55 which coils are similarly energizable to activate the selected time pattern for such units, just as already described with respect to unit A. In the B and C units, the corresponding discs are marked 163, 164, 165 and 166, 167 and 168; the ears 189, 190, 191 and 192, 193, 194; and the "stationary" stops 195, 196, 197 and 198, 199, 200.

As also illustrated, one side of each of coils 174, 177, 180 is connected to the line 20 through a switch 201; coils 175, 178, 181 are all connected to line 20 through switch 202; and coils 176, 179, 182 are all connected to line 20 through switch 203. The other sides of the coils are connected to the other line 51, as indicated or as may be convenient. Thus, by means of the switches 65 201, 202, 203, which can be located at any desired remote control center, all the units of the illustrated three-unit controller can be caused to operate in accordance with any one of the 70 three timing patterns predetermined by the settings of the discs on the respective shafts.

And the same pattern-selecting switches can, of course, be connected to control the stop coils of as many different controllers as may be desired, as indicated by the dash line extensions of wires 204, 205, 206.

While the described controller and selective control apparatus can be embodied in many forms, the construction of the controller itself can be assumed to be essentially the same as that illustrated in my said prior patent, excepting only as respects the means for determining the initial stop positions of the control shafts and the means for adjusting the stops to vary the time settings of the green signals, which means are illustrated herein and are described below in detail in one preferred embodiment. For the reason noted, the mechanical components of the controller, which are the same as in my prior patent, will not be described in detail herein. For present purposes it is sufficient to note (with particular reference to Fig. 2) that the single unit illustrated includes a mounting plate 207 and face plate 208 united by spacers 209. An adjusting knob 210 movable over a second scale on the face plate 208 corresponds to the adjusting screw 140 of the Fig. 1 diagram. Shafts 211, 212 correspond to diagram shafts 66, 75; motor 213 to diagram motor 69; gear reduction housing 214 to the diagram housing 72; detent 215 to diagram detent 121; coil 216 to diagram coil 125; cam 217 to diagram cam 62.

Coming now to the selective control and adjustment means of the present invention: Shaft 211 is shown extended through a large aperture 219 in face plate 208 and on a hub portion 220 of the shaft at its forward end is mounted a disc generally designated 221. This disc is composed of a series of annular elements (corresponding to the discs 165, etc. of the Fig. 1 diagram) one for each timing pattern. In this instance, three such elements are shown, marked 222, 223, 224. The perimeter of the shaft hub and the mating edges of the several annular elements are formed with complementary steps (as indicated, for example, at 225) and the elements are normally locked to the shaft hub and to each other, as by the overlapping heads of screws 226, 227, 228. Projecting from the rear face of each annular element is a stud (which corresponds to the ears or stop elements 168, etc. of the Fig. 1 diagram), the stud 229 of element 224 appearing in Fig. 2.

On the front face of mounting plate 207 are three circumferentially spaced coils 230, 231, 232, corresponding to diagram coils 177, etc., and similarly controlling pivotally mounted "stationary" stop elements 233, 234, 235 so positioned that when any one of the coils is energized its stop element is moved into the path of the corresponding one of the annular element stops. Springs (such as indicated at 236 in Fig. 2) serve to bias the stationary stop elements to their inactive positions.

Suitably located on the front of the unit is an indicator, such as index 237 on the shaft hub; and, as shown in Fig. 3, the peripheral portions of the several annular elements of disc 221 are calibrated. It being assumed that the speed of shaft 211 is such that it would make one complete revolution in a minute, the annular element calibrations are appropriate subdivisions, in seconds.

The ease with which the stops can be set to provide three different durations for the green

signal will be apparent. By loosening screws 226 and rotating the disc element bodily, the desired time figure on the innermost annular element 222 is brought opposite index 237 and the screws re-tightened. Upon loosening screws 227, the remaining annular element can be rotated about element 222 and the desired time figure on element 223 brought opposite index 237. After screws 227 have been re-tightened, the holding screws 228 of the outer element are loosened and that element similarly adjusted to its desired setting.

Thereafter, as described in connection with the Fig. 1 diagram, any one of the three stops can be activated by the energizing of its coil and the corresponding time pattern thereby initiated.

As will be apparent, the described system is such that the change from one time pattern to another does not involve any sudden switching of the signal lights themselves and it is quite unnecessary to provide any such coordinating means as are ordinarily required in other systems commonly in use.

In the system exemplified in the Fig. 1 diagram, all three of the available time patterns are shown as being subject to remote control by means of switches 201, 202, 203; but one of the control switches may be eliminated and provision made whereby the de-energization of two of the time pattern circuits automatically makes the third pattern effective.

Such an arrangement is illustrated schematically in Fig. 4, in which the three pivoted stop elements 240, 241, 242 correspond to the stop elements 171, 172, 173 of unit A of the Fig. 1 diagram. It is contemplated, of course, that stops similar to 240, 241, 242 would likewise be provided for each of the other units of the controller but since their action is identical, only one set need be described.

In the Fig. 4 arrangement, even though the stop elements provide for three time patterns, only two remote control switches 243, 244 are provided and shown as controlling, respectively, the energization of solenoid coils 245, 246 from mains 247, 248. As in the arrangement previously described, the closure of switch 243 or 244 renders effective stop element 240 or 242 (and their counterparts in as many other units and controllers as are in the system).

Whereas stop elements 240 and 242 are biased to their inactive or ineffective positions, stop element 241, on the other hand, is biased to its active or effective position, as by spring 249, but is moved to and held in its inactive position whenever one or the other of coils 245, 246 is energized. When neither of these coils is energized, stop element 241 is moved to its active position by its spring 249. For simplicity of illustration, these functions are schematically shown as being served by stops 250, 251 projecting laterally from the armatures 252, 253 of coils 245, 246 and positioned (when either coil is energized) to block the upward movement of a cross bar 254 which is connected by link 255 to stop element 241. As will be apparent, when coils 245 and 246 are both de-energized, stop 250 will be moved up to its dotted line position and stop 251 to its full line position, thereby permitting cross bar 254 to move up and stop element 241 to take up its active (dotted line) position. Subsequent energization of either coil 245 or coil 246 will, through the laterally projecting stop on its armature,

move cross bar down and de-activate stop element 241.

If the system should be designed to provide only two time patterns then, of course, one of the coils, stop elements and control switches could be dispensed with. For example, in a two pattern system, switch 244, coil 246 and stop element 242 could be dispensed with, stop element 240 being rendered effective by the closure of switch 243 and stop element 241 being rendered effective upon the opening of switch 243.

In the light of the foregoing illustrative description, the following is claimed:

1. In a controller unit of the kind including a control shaft adapted to be rotated forwardly from a stop position to a limit position and thence backwardly to its stop position and in which a green signal is adapted to be de-energized at a predetermined point in the forward movement of the shaft, the improvement which comprises: a motor having connections for driving the shaft in its forward movement; a spring having connections for driving the shaft in its backward movement; a plurality of stop means for limiting the backward, spring driven movement only of the shaft, said means being located at circumferentially spaced points with respect to the shaft axis; and means for selectively activating said stop means.

2. In a controller unit of the kind including a control shaft adapted to be rotated forwardly from a stop position to a limit position and thence backwardly to its stop position and in which a green signal is adapted to be de-energized at a predetermined point in the forward movement of the shaft, the improvement which comprises: a motor having connections for driving the shaft in its forward movement; a spring having connections for driving the shaft in its backward movement; a first set of stop elements; a second set of stop elements; the elements of at least one of said sets being circumferentially spaced about the shaft axis; one of said sets of stops being mounted for rotation with the shaft; and means for moving the stop elements of one set into and out of engaging position with respect to stop elements of the other set, the stop elements of one set being yieldable to permit movement of the shaft in its forward, motor driven direction.

3. In a controller unit of the kind including a control shaft adapted to be rotated forwardly from a stop position to a limit position and thence backwardly to its stop position and in which a green signal is adapted to be de-energized at a predetermined point in the forward movement of the shaft, the improvement which comprises: a motor having connections for driving the shaft in its forward movement; a spring having connections for driving the shaft in its backward movement; a plurality of stop means rotatable with the shaft and spaced radially with respect to the shaft axis; stationary stop means for engagement with the rotatable stop means; and means for effecting relative movement between the rotatable and stationary stop means into and out of position to interengage upon backward rotation only of the shaft.

4. In a controller unit of the kind including a control shaft adapted to be rotated forwardly from a stop position to a limit position and thence backwardly to its stop position and in which a green signal is adapted to be de-energized at a predetermined point in the forward movement of the shaft, the improvement which comprises: a motor having connections for driving the shaft

in its forward movement; a spring having connections for driving the shaft in its backward movement; a plurality of stop means for limiting the backward movement of the shaft; means for adjusting said stop means circumferentially about the shaft axis; and means for selectively activating said stop means.

5. In a controller unit of the kind including a control shaft adapted to be rotated forwardly from a stop position to a limit position and thence backwardly to its stop position and in which a green signal is adapted to be de-energized at a predetermined point in the forward movement of the shaft, the improvement which comprises: a motor having connections for driving the shaft in its forward movement; a spring having connections for driving the shaft in its backward movement; a set of stop elements mounted to rotate with the shaft and adjustable relatively to each other about the shaft axis; a set of stationary stop elements; and means for moving stop elements of one set into and out of position to engage stop elements of the other set to limit backward movement of the shaft.

6. In a controller unit of the kind including a control shaft adapted to be rotated forwardly from a stop position to a limit position and thence backwardly to its stop position and in which a green signal is adapted to be de-energized at a predetermined point in the forward movement of the shaft, the improvement which comprises: a first set of stop elements; a second set of stop elements; the elements of at least one of said sets being circumferentially spaced about the shaft axis; one of said sets of stops being mounted for rotation with the shaft; and means for moving the stop elements of one set into and out of engaging position with respect to stop elements of the other set, the elements of one set being flexible and thereby adapted to yield to engagement by the elements of the other set on rotation of the shaft in a forward direction.

7. In a controller unit of the kind including a control shaft adapted to be rotated forwardly from a stop position to a limit position and thence backwardly to its stop position and in which a green signal is adapted to be de-energized at a predetermined point in the forward movement of the shaft, the improvement which comprises: a plurality of stop means for limiting the backward movement of the shaft and arranged to yield to permit forward movement of the shaft, said means being located at circumferentially spaced points with respect to the shaft axis; and a separately energizable coil for activating each of said stop means.

8. In a selective control apparatus, the combination of a rotatable shaft; a disc unit secured to the shaft and comprising a plurality of concentric annular elements; locking means for releasably locking adjacent elements to one another; stop means carried by each of said annular elements; a plurality of stationary stop elements; and means for moving each of said stationary stop elements into and out of position for engagement by one of the annular element stop means.

9. In a selective control apparatus, the combination of a rotatable shaft; a disc unit secured to the shaft and comprising a plurality of concentric annular elements; locking means for releasably locking adjacent elements to one another; stop means carried by each of said annular elements; a plurality of stationary stop elements mounted adjacent the face of the disc carrying

said first-mentioned stop means and circumferentially spaced with respect to the shaft axis; and means for moving each of said stationary stop elements into and out of position for engagement by one of the annular element stop means.

10. In a selective control apparatus, the combination of a rotatable shaft; a disc unit secured to the shaft and comprising a plurality of concentric annular elements; locking means for releasably locking adjacent elements to one another; stop means carried by each of said annular elements; a plurality of stationary stop elements; a coil for activating each of said stationary stop elements relatively to a corresponding stop means carried by the disc; and individual circuits for controlling the energizing of said coils.

11. In a selective control apparatus, the combination of a rotatable shaft; a disc unit secured to the shaft and comprising a plurality of concentric, annular elements having overlapping steps formed around their adjacent peripheries; means for locking each element to its adjacent element; stop means carried by each of said annular elements; a plurality of stationary stop elements; and means for moving each of said stationary stop elements into and out of position for engagement by one of the annular element stop means.

12. In a controller unit of the kind including a control shaft adapted to be rotated forwardly from a stop position to a limit position and thence backwardly to its stop position and in which a green signal is adapted to be de-energized at a predetermined point in the forward movement of the shaft, the improvement which comprises: a plurality of stop means for limiting the backward movement of the shaft, said means being located at circumferentially spaced points with

respect to the shaft axis, and each stop means including an element movable into and out of active position; a coil energizable to move the element of one of the stop means into its said active position; and control means for the movable element of another of said stop means responsive to the de-energization of said coil.

- 5 13. In a controller unit of the kind including a control shaft adapted to be rotated forwardly
10 from a stop position to a limit position and thence backwardly to its stop position and in which a green signal is adapted to be de-energized at a predetermined point in the forward movement of the shaft, the improvement which comprises:
15 a plurality of stop means for limiting the backward movement of the shaft, said means being located at circumferentially spaced points with respect to the shaft axis; a coil energizable to activate at least one of said stop means; a switch 20 for controlling said coil; and means responsive to the opening of the switch adapted to activate another of said stop means.

JOHN J. ALLES.
